US0D1013500S

(12) **United States Design Patent** (10) **Patent No.:** **US D1,013,500 S**
(45) **Date of Patent:** **** Feb. 6, 2024**

(54) **STAPLE**

(71) Applicant: **MILWAUKEE ELECTRIC TOOL CORPORATION**, Brookfield, WI (US)

(72) Inventors: **David S. Koper**, Milwaukee, WI (US);
Nathan Bandy, Wauwatosa, WI (US);
Andrew R. Wyler, Pewaukee, WI (US)

(73) Assignee: **MILWAUKEE ELECTRIC TOOL CORPORATION**, Brookfield, WI (US)

(**) Term: **15 Years**

(21) Appl. No.: **29/868,748**

(22) Filed: **Dec. 13, 2022**

Related U.S. Application Data

(62) Division of application No. 29/751,519, filed on Sep. 22, 2020, now Pat. No. Des. 976,093.

CLAIM

We claim the ornamental design for a staple, as shown and described.

DESCRIPTION

FIG. 1 is a front perspective view of the first embodiment of a staple in accordance with the present invention.

FIG. 2 is a front view of the staple of FIG. 1.

FIG. 3 is a rear view of the staple of FIG. 1.

FIG. 4 is a right-side view of the staple of FIG. 1.

FIG. 5 is a left-side view of the staple of FIG. 1.

FIG. 6 is a top view of the staple of FIG. 1.

FIG. 7 is a bottom view of the staple of FIG. 1.

FIG. 8 is a front perspective view of the second embodiment of a staple in accordance with the present invention.

FIG. 9 is a front view of the staple of FIG. 8.

FIG. 10 is a rear view of the staple of FIG. 8.

FIG. 11 is a right-side view of the staple of FIG. 8.

FIG. 12 is a left-side view of the staple of FIG. 8.

FIG. 13 is a top view of the staple of FIG. 8; and,

FIG. 14 is a bottom view of the staple of FIG. 8.
